UNITED STATES PATENT OFFICE.

PAUL P. FEIT, OF CANTON, OHIO, ASSIGNOR TO THE TIMKEN ROLLER BEARING COMPANY, OF CANTON, OHIO, A CORPORATION OF OHIO.

AIR-CONTROL DEVICE.

Application filed July 5, 1924. Serial No. 724,535.

My invention relates to air control devices for automatic machinery, such as the automatic machines used for burnishing roller bearing parts and it has for its principal object a device which is automatic in its operation, which may be adjusted to suit different conditions, and which insures that each article burnished will receive treatment that is identical with that of every other article. 5 The invention consists in the air control device and in the parts and combinations of parts hereinafter described and claimed.

In the accompanying drawings, which form part of this specification, and wherein 10 like reference numerals indicate like parts wherever they occur.

Fig. 1 is a top plan view of an air control device embodying my invention,

Fig. 2 is an elevation thereof, certain parts 15 being shown in vertical section,

Fig. 3 is a vertical sectional view on the line 3—3 of Fig. 1,

Fig. 4 is a vertical sectional view on the line 4—4 of Fig. 1,

Fig. 5 is a horizontal sectional view on the line 5—5 of Fig. 3,

Fig. 6 is a horizontal sectional view on the line 6—6 of Fig. 3,

Fig. 7 is a vertical sectional view on the line 7—7 of Fig. 3, and

Fig. 8 is a detail view of the slide valve.

Secured to a suitable frame 1 as by screws 2 and dowels 3 is a hollow body member 4 in the enlarged bore of which is disposed a piston 5 that is provided with an upwardly extending operating rod 6 and with a downwardly extending slide valve 7 that works in a valve sleeve 8 in the body member 4. Preferably the bore of the body member is provided with a bushing 9 that constitutes the cylinder for the piston 5.

Secured to the body member 4 as by screws 10 is a valve housing 11 that is provided with four air chambers; an air inlet chamber 12 that is provided with an opening into which is threaded the end of a pipe 13 that supplies air to said chamber; a chamber 14 above said chamber and separated therefrom by a partition 15 in which is an opening 16 that may be closed by means of a spring-pressed valve 17; a chamber 18 that has an opening into which is threaded a pipe 19 that leads to the cylinder C of the burnishing machine or the like that operates the burnishing tool T 55 for burnishing a roller bearing cone W or the

like; and a chamber 20 that is separated from said cylinder supply chamber 18 by a partition 21 in which is an opening 22 that may be closed by a spring-pressed valve 23 and is also provided with an exhaust pipe 24. 60

The body member 4 is provided with two air chambers; a chamber 25 that is in direct communication with said second chamber 14 of the valve housing through a passageway 25^a and a second chamber 26 that may be connected with said chamber by means of valve mechanism hereinafter described. Said second chamber 26 in said body member is in direct communication with the cylinder supply chamber 18 of said valve housing 11 70 through a passageway 26^a. Said second chamber 26 is also in communication by means of a bleed opening 27 with the lower end of the cylinder 9 in which the piston 5 works. The size of said bleed opening may 75 be controlled by a needle valve 28.

The valve 17 that controls the opening between the air inlet chamber 12 and the second chamber 14 of the valve housing 11 is mounted at the lower end of a stem 29 that projects upwardly through the top of the housing 11. The valve 17 is normally held against its seat by means of a spring 30 that is interposed between the end of the valve 17 and a cap 31 that is threaded into the valve 80 housing 11. The stem 29 of the valve 17 is provided with a plurality of oil grooves 32, so that a seal is formed to prevent the escape of air from the air chamber 14. 85

The exhaust valve 23 of the air chamber 90 18 (the chamber that supplies air to the cylinder of the burnishing machine) is likewise normally held against its seat by means of a spring 33 interposed between the valve and a cap 34 threaded into the valve housing 11. Said valve is provided with a stem 35 that projects upwardly through the housing and is provided with a plurality of oil grooves 36. 95

Pivotal secured to the valve housing 11 100 as by a pin 37 is an operating rod 38 that has two operating arms 39, one for said valve 17 that controls the inlet of air and the other for said valve 23 that controls the exhaust of air. Said operating rod 38 is secured to the frame 1 by means of a spring 40 that normally holds the operating rod 38 in such position that the arm that controls the exhaust valve 23 is depressed and holds said valve in its downward position, so that 105 110

air may exhaust freely from the cylinder of the machine and from the cylinder supply chamber 18 and the exhaust chamber 20 of the valve housing 11.

5 Pivottally mounted in the frame 1 as by being secured to a pivot rod 41^a by a pin 41^b is a lever 41 that is provided with a plurality of weights 42 whereby the force needed to raise said lever may be varied. The end 10 of said lever 41 works in a slot in a stop member 43, whereby the upward and downward movement of the lever is limited.

The operating rod 38 is moved into position to depress the inlet valve 17 and hold 15 it open by means of a suitable pull rod (not shown in the drawings). Loosely mounted on said pivot 41^a is a latch member 44 that is adapted to engage a pin 45 on the operating rod 38 to hold it in this position.

20 A stop pin 44^a on said pivot rod 41^a engages a stop pin 44^b on said latch member 44. Thus said latch member may be raised independently of the lever 41 to clear the pin 45, and is raised with said lever 41 by means 25 of the pins 44^a and 44^b.

The sleeve 8 in which the slide valve 7 works constitutes the partition between the two air chambers 25 and 26 of the body member. Said valve 7 is provided with an annular groove 46 and said sleeve is provided 30 with a lower pair of openings 47 opening respectively into said air chambers 25 and 26 and with an upper pair of openings 48 opening respectively into said air chambers. 35 The lower end of said valve 7 is provided with oil grooves 49 thereby forming an air-tight seal for said valve. The lower end of the valve 7 projects into a hollow cap 50 that is threaded into the body member.

40 The upper end of said piston rod 6 is provided with a slot 51 in which rests a lever 52 that is pivotally secured at one end to the frame 1 and to the other end of which is secured a spring 53 that is also secured to a 45 pin 54 on the body member 4. By the pressure of said lever 52 on the top thereof, said piston rod 6 is normally held in its lower-most position and the annular groove 46 of the slide valve 7 registers with the lower 50 pair of openings 47 in the sleeve 8, so that the air may pass from the chamber 25 of the body (which receives air from the second chamber 14 of the valve housing 11) to the chamber 26 of the body and from 55 thence to the cylinder supply chamber 18 of the housing 11. A portion of the air entering said chamber 26 passes into the cylinder 9 of the body member to raise the piston 5.

60 Vertically disposed in the weighted lever 41 is a plunger 55 that has a stem 56 on which is disposed a coil spring 57 and that has an enlarged portion 58 which prevents it from dropping out of the lever and which 65 constitutes an abutment for the end of said

spring. A housing member 59 for the stem 56 is secured to said lever 41 and is provided with a threaded cap 60 against which the spring bears. The pressure of the spring 57 may be adjusted by turning said cap. The 70 end of said plunger 55 is in line with said lever 52 and is engaged thereby as the piston 5 and lever 52 are raised. The resistance of the spring 57 causes the piston 5 and lever 75 52 to rise more slowly after said lever engages the plunger 55.

The operation of the device is as follows: In the normal positions of the parts, as has been stated, the inlet valve 17 is closed and the exhaust valve 23 is open, so that there is 80 no pressure in the air cylinder of the machine. The operating rod 38 is manually moved so as to cause an arm 39 thereof to open the inlet valve 17 and to permit the exhaust valve 23 to close. The operating rod 38 is held in 85 this position by the latch 44. Thus air enters the inlet chamber 12 of the valve housing 11, passes therefrom to the second chamber 14 and to the chamber 25 of the body member, whence it passes through the openings 47 and 90 the annular groove 46 of the slide valve 7 into the other chamber 26 of the body member and thence to the cylinder supply chamber 18 of the valve housing 11 and to the air cylinder that operates the burnishing machine. Thus 95 air passes quickly into the cylinder of the burnishing machine and rapidly builds up an initial pressure therein and brings the burnishing tool into operative position. As the air pressure in the cylinder supply chamber 100 18 is built up, a portion of the air passes therefrom through the bleed opening 27 into the lower end of the cylinder 9 of the body member where it causes the piston 5 to rise. As said piston 5 rises, it carries with it the 105 slide valve 7, closing said first openings 47 and partly opening the second openings 48. Thus air continues to flow from the air inlet chamber 12 through the ways above described into the cylinder supply chamber 18; so that 110 the pressure in said chamber 18 and in the operating cylinder of the machine is at first maintained and then gradually built up and the burnishing tool is moved further toward the work. As the piston 5 rises further, the 115 annular groove registers more and more fully with the upper openings 48, thus building up the pressure in the cylinder supply chamber 18 and in the operating cylinder.

As the piston 5 and lever 52 rise, the lever 120 presses upwardly against the plunger 55 of the weighted lever 41 and gradually raises it. The continued movement of the piston 5 and lever 52 causes the outer end of the lever 52 to engage a roller 61 that is secured to the 125 weighted lever 41. When the lever 52 is operating both against the plunger 55 and the roller 61 of the weighted lever 41, further movement is prevented until the pressure in the cylinder supply chamber 18 and in the 130

cylinder of the machine and also in the cylinder 9 in which the piston works is built up sufficiently to overcome the force of the weights 42 on the weighted lever 41. When 5 the pressure is sufficient to overcome this force, the weighted lever 41 is swung upwardly thus withdrawing the latch 44 from the pin 45 of the operating rod 38 and permitting said rod to swing to its normal position, in 10 which the inlet valve 17 is closed and the exhaust valve 23 is open. Thus the pressure of the machine cylinder and of the cylinder supply chamber is exhausted through the valve opening and through the exhaust chamber 15 of the body member and the operation of the machine is stopped. Adjustments may be made by regulating the size of the bleed opening, by adjusting the spring on the plunger, and by adjusting the weights on the weighted 20 lever.

The herein-described air control device has numerous advantages. It secures uniformity of treatment of the articles being operated on. The pressure is very rapidly built up to a 25 point sufficient to cause the burnishing machine to begin operations. The pressure then is very gradually built up in the cylinder supply chamber and in the operating cylinder of the machine, so that the work of the machine continues and finally when the pressure reaches a maximum, the air supply is exhausted and the operation of the machine 30 stopped. The device is automatic, except for the step of setting it in operation. Nothing 35 is left to the judgment of the machine operator as to the extent of time the machine shall operate or the degree of pressure that is admitted to the machine. Obviously numerous changes may be made without departing from 40 the invention and I do not wish to be limited to the precise construction shown.

What I claim is:

1. An air control device comprising an air supply, an air receiving chamber communicating with said air supply, an inlet valve for controlling the communication between said chamber and said air supply, a supply chamber for the operating cylinder of a machine, a passageway for air from said receiving chamber to said supply chamber, an exhaust opening in the wall of said supply chamber, an exhaust valve for controlling said exhaust opening, a lever for controlling said inlet valve and said exhaust valve, means for normally holding said lever in such position that the exhaust valve is open and the inlet valve is closed, means for latching said valve in such position that the inlet valve is open and the exhaust valve is closed and means controlled by the pressure in the system for unlatching said lever. 55 60

2. An air control device comprising an air receiving chamber, an inlet valve for controlling the admission of air to said receiving chamber, a supply chamber for sup-

plying air to the operating cylinder of a machine, a cylinder communicating with said supply chamber, a piston in said cylinder adapted to be raised by air passing into said cylinder from said supply chamber, and a valve for controlling the passage of air from said receiving chamber to said supply chamber, said valve being connected with said piston to move therewith. 70

3. An air control device comprising an air receiving chamber, an inlet valve for controlling the admission of air to said receiving chamber, a lever for operating said valve, means for holding said valve operating lever in one position, a supply chamber for supplying air to the operating cylinder of a machine, an intermediate passageway located in the path of the air traveling from said receiving chamber to said supply chamber, a partition in said passageway, a slide valve in said partition, said valve being provided with an annular groove, and said partition being provided with spaced circular series of openings adapted to communicate with said groove, 90 a cylinder communicating with said supply chamber, a piston in said cylinder, said piston being connected with said slide valve, and means actuated by said piston for releasing the holding means for said valve 95 operating lever.

4. An air control device comprising an air receiving chamber, an inlet valve for controlling the admission of air to said receiving chamber, a supply chamber for supplying air to the operating cylinder of a machine, an intermediate passageway, a partition in said passageway, a slide valve in said partition, said valve being provided with an annular groove, and said partition being provided with spaced sets of openings 100 adapted to communicate with said groove, a cylinder communicating with said supply chamber, a piston in said cylinder, said piston being connected with said slide valve, 110 the distance between the upper and lower sets of openings being slightly less than the width of said groove, whereby the upper openings are slightly uncovered before the lower openings are entirely closed, an exhaust valve for said supply chamber, means for operating said inlet and exhaust valves, and means actuated by said piston for initiating movement of said valve operating means to close said inlet valve and 115 open said exhaust valve.

5. An air control device comprising an air receiving chamber, an inlet valve for controlling the admission of air to said receiving chamber, a supply chamber for supplying air to the operating cylinder of a machine, an exhaust valve for said supply chamber, an intermediate passageway, a partition in said passageway, a slide valve in said partition, said valve being provided 125 130

with an annular groove, and said partition being provided with spaced sets of openings adapted to communicate with said groove, whereby when the groove is in communication with the openings of either set, air may pass from the receiving chamber through the intermediate passageway and into the supply chamber, means for operating said inlet and exhaust valves, and means operated by the pressure in said supply chamber for initiating movement of said valve operating means to close said inlet valve and open said exhaust valve.

6. An air control device comprising an air receiving chamber, an inlet valve for controlling the admission of air to said receiving chamber, a supply chamber for supplying air to the operating cylinder of a machine, an exhaust valve in said supply chamber, a lever for operating said inlet and exhaust valves, an intermediate passageway, a partition in said passageway, a slide valve in said partition, said valve being provided with an annular groove, and said partition being provided with spaced sets of openings adapted to communicate with said groove whereby when either set of openings is in communication with said groove, air may pass through said intermediate passageway into said supply chamber, a cylinder communicating with said supply chamber, a piston in said cylinder, said piston being connected with said slide valve, and means operated by said piston for initiating movement of said valve operating lever.

7. In an air control device, an air receiving chamber, an inlet valve for controlling the admission of air to said receiving chamber, a supply chamber communicating with said receiving chamber, an exhaust valve for said supply chamber, a lever for operating said valves, means for latching said valve operating lever in position so that the inlet valve is open and the exhaust valve is closed, a cylinder communicating with said supply chamber, a piston in said cylinder and adapted to be raised as the pressure is increased, and means operated by said piston for unlatching said valve operating lever.

8. An air control device comprising an air supply, an air receiving chamber communicating with said air supply, an inlet valve for controlling the communication between said chamber and said air supply, a supply chamber for the operating cylinder of a machine, a passageway for air from said receiving chamber to said supply chamber, an exhaust opening in the wall of said supply chamber, an exhaust valve for controlling said exhaust opening, a lever for controlling said inlet valve and said exhaust valve, means for normally holding said lever in such position that the exhaust valve is open and the inlet valve is closed, means for latching said valve in such position that the inlet valve is open and the exhaust valve is closed, a cylinder commun-

cating with said supply chamber, a piston in said cylinder and adapted to be raised as the pressure is increased, and means operated by said piston for unlatching said valve operating lever.

9. An air control device comprising an air supply, an air receiving chamber communicating with said air supply, an inlet valve for controlling the communication between said chamber and said air supply, a supply chamber for the operating cylinder of a machine, a passageway for air from said receiving chamber to said supply chamber, an exhaust opening in the wall of said supply chamber, an exhaust valve for controlling said exhaust opening, a lever for controlling said inlet valve and said exhaust valve, means for normally holding said lever in such position that the exhaust valve is open and the inlet valve is closed, a cylinder communicating with said supply chamber, a piston in said cylinder, a spring-pressed lever engaging the top of said piston, a lever adapted to be engaged by said spring-pressed lever and provided with adjustable weights, and a latch member operatively connected with said weighted lever adapted to engage said valve operating lever to hold it in such position that the inlet valve is open, and to be disengaged therefrom when said weighted lever is swung upwardly by said spring-pressed lever.

10. An air control device comprising an air inlet chamber, an air receiving chamber communicating with said inlet chamber, an inlet valve for controlling the communication between said chambers, a supply chamber for the operating cylinder of a machine, a passageway for air from said receiving chamber to said supply chamber, an exhaust chamber communicating with said supply chamber, an exhaust valve for controlling the communication between said exhaust chamber and said supply chamber, a lever for operating said valves, resilient means for normally holding said lever in such position that the inlet valve is closed and the exhaust valve is open, means for latching said valve operating lever in such position that the inlet valve is open and the exhaust valve is closed, and means operated by the pressure of the air for unlatching said lever, said means comprising a cylinder communicating with said supply chamber, a piston in said cylinder, a spring-pressed lever engaging the top of said piston, a lever adapted to be engaged by said spring-pressed lever and provided with adjustable weights, said weighted lever having said latching means operatively connected therewith, and a spring-pressed plunger in said weighted lever for engaging the upper edge of said spring-pressed lever.

11. An air control device comprising an air inlet chamber, an air receiving chamber communicating with said inlet chamber, an inlet valve for controlling the communication

- between said chambers, a supply chamber for supplying air to the operating cylinder of a burnishing machine or the like, an exhaust chamber, an exhaust valve for controlling the communication between said exhaust chamber and said supply chamber, intermediate chambers, one of said intermediate chambers opening into said supply chamber, and one of said intermediate chambers opening into said air receiving chamber, an exhaust chamber communicating with said supply chamber, a partition between said intermediate chambers, a slide valve in said partition, said valve having an annular groove therein and said partition having two sets of holes adapted to communicate with said annular groove, a lever for operating said inlet and exhaust valves, a spring for normally holding said lever in position so that the inlet valve is closed and the exhaust valve is open, a lever pivoted at one end and provided with adjustable weights, means connected with said weighted lever for latching said valve operating lever when it is moved into position so that the inlet valve is open and the exhaust valve is closed, a cylinder communicating with said supply chamber through a bleed opening, a piston in said cylinder and connected to said slide valve, a lever pivoted at one end and having a spring secured to the outer end tending to keep said lever in its lowermost position, said lever resting in a slot provided therefor in the projecting upper end of said piston, said weighted lever being provided with a roller adapted to be engaged by the outer end of said spring-pressed lever, a spring-pressed plunger projecting from the underside of said weighted lever and adapted to engage the upper edge of said spring-pressed lever, and means for varying the pressure on said spring-pressed plunger.
13. In combination with a burnishing machine, or the like comprising a tool and a cylinder for operating the same, an air receiving chamber, an inlet valve for controlling the admission of air to said receiving chamber, a supply chamber for supplying air to said operating cylinder of the machine, an intermediate passageway, a partition in said passageway, a slide valve in said partition, said valve being provided with an annular groove, and said partition being provided with spaced sets of openings adapted to communicate with said groove, whereby when the groove is in communication with the openings of either set, air may pass from the receiving chamber through the intermediate passageway and into the supply chamber and means controlled by the air pressure in said cylinder supply chamber for operating said slide valve.
14. In combination with a burnishing machine or the like comprising a tool and an air cylinder for operating the same, an air supply, an air receiving chamber communicating with said air supply, an inlet valve for controlling the communication between said chamber and said supply, a supply chamber for supplying air to said operating cylinder, a passageway for air from said receiving chamber to said supply chamber, a slide valve in said passageway, an exhaust opening in the wall of said supply chamber, an exhaust valve for controlling said exhaust opening, a lever for operating said inlet and exhaust valves, a spring for normally holding said lever in position so that the inlet valve is closed and the exhaust valve is open, means for latching said valve operating lever when it is moved into position so that the inlet valve is open and the exhaust valve is closed, a cylinder communicating with said supply chamber through a bleed opening, a piston in said cylinder and connected to said slide valve, and a lever pivoted at one end and having a spring secured to the outer end tending to keep said

12. An air control device comprising an air inlet chamber, an air receiving chamber communicating with said inlet chamber, an inlet valve for controlling the communication between said chambers, a supply chamber for supplying air to the operating cylinder of a burnishing machine or the like, an exhaust chamber, an exhaust valve for controlling the communication between said exhaust chamber and said supply chamber. Intermediate chambers, one of said intermediate chambers opening into said supply chamber, and one of said intermediate chambers opening into said air receiving chamber, an exhaust chamber communicating with said supply chamber, a partition between said intermediate chambers, a slide valve in said partition, said slide valve having an annular groove therein and said partition having two sets of holes adapted to communicate with said annular groove, a lever for operating said inlet and exhaust valves, a spring for normally holding said lever in position so that the inlet valve is closed and the exhaust valve is open, a lever pivoted at one end and provided with adjustable weights, means connected with said weighted lever for latching

lever in its lowermost position, said lever resting in a slot provided therefor in the projecting upper end of said piston.

15. In combination with a burnishing machine or the like comprising a tool and an air cylinder for operating the same, an air supply, an air receiving chamber communicating with said air supply, an inlet valve for controlling the communication between said chamber and said supply, a supply chamber for supplying air to said operating cylinder, a passageway for air from said receiving chamber to said supply chamber, an exhaust opening in the wall of said supply chamber, an exhaust valve for controlling said exhaust opening, a lever for operating said inlet and exhaust valves, a spring for normally holding said lever in position so that the inlet valve is closed and the exhaust valve is open, means for latching said valve operating lever when it is moved into position so that the inlet valve is open and the exhaust valve is closed, and means controlled by the pressure in the system for unlatching said lever.

16. An air control device comprising an air supply, an air receiving chamber communicating with said air supply, an inlet valve for controlling the communication between said chamber and said air supply, a supply chamber for the operating cylinder of a machine, a passageway for air from said receiving chamber to said supply chamber, an exhaust opening in the wall of said supply chamber, an exhaust valve for controlling said exhaust opening, a lever for controlling said inlet valve and said exhaust valve, means for normally holding said lever in such position that the exhaust valve is open and the inlet valve is closed, a cylinder communicating with said supply chamber, a piston in said cylinder, a spring pressed lever engaging the top of said piston, a lever secured to a pivotally mounted rod and provided with weights, said weighted lever being adapted to be engaged by said spring pressed lever, a latch member loosely mounted on said pivot rod of said weighted lever, a pin secured to said pivot rod and a pin secured to said latch member, said latch member being adapted to engage said valve operating lever to hold it in such position that the inlet valve is open, and said latch member being disengaged from said valve operating lever by means of the engagement of said pins when said weighted lever is swung upwardly by said spring pressed lever.

17. An air control device comprising an air supply, an air receiving chamber communicating with said air supply, an inlet valve for controlling the communication between said chamber and said air supply, a supply chamber for the operating cylinder of a machine, a passageway for air from said

receiving chamber to said supply chamber, an exhaust opening in the wall of said supply chamber, an exhaust valve for controlling said exhaust opening, a lever for controlling said inlet valve and said exhaust valve, means for normally holding said lever in such position that the exhaust valve is open and the inlet valve is closed, a cylinder communicating with said supply chamber, a piston in said cylinder, a spring pressed lever engaging the top of said piston, a lever secured to a pivotally mounted rod and provided with weights, a contact roller on said weighted lever adapted to be engaged by said spring pressed lever, a latch member loosely mounted on said pivot rod of said weighted lever, a pin secured to said pivot rod and a pin secured to said latch member, said latch member being adapted to engage said valve operating lever to hold it in such position that the inlet valve is open, and said latch member being disengaged from said valve operating lever by means of the engagement of said pins when said weighted lever is swung upwardly by said spring pressed lever.

18. An air control device comprising an air supply, an air receiving chamber communicating with said air supply, an inlet valve for controlling the communication between said chamber and said air supply, a supply chamber for the operating cylinder of a machine, a passageway for air from said receiving chamber to said supply chamber, an exhaust opening in the wall of said supply chamber, an exhaust valve for controlling said exhaust opening, a lever for controlling said inlet valve and said exhaust valve, means for normally holding said lever in such position that the exhaust valve is open and the inlet valve is closed, a cylinder communicating with said supply chamber, a piston in said cylinder, a spring pressed lever engaging the top of said piston, a lever secured to a pivotally mounted rod and provided with weights, a spring pressed plunger projecting from the bottom of said weighted lever, a contact roller secured to the underside of said weighted lever, said plunger and said roller being adapted to be engaged in succession by said spring pressed lever, a latch member loosely mounted on said pivot rod of said weighted lever, a pin secured to said pivot rod and a pin secured to said latch member, said latch member being adapted to engage said valve operating lever to hold it in such position that the inlet valve is open, and said latch member being disengaged from said valve operating lever by means of the engagement of said pins when said weighted lever is swung upwardly by said spring pressed lever.

Signed at Canton, Ohio, this 30th day of June, 1924.

PAUL P. FEIT,
